his Attorney.

UNITED STATES PATENT OFFICE.

JAMES S. HILYARD, OF COLUMBUS, OHIO.

WASHING-MACHINE.

SPECIFICATION forming part of Letters Patent No. 570,853, dated November 3, 1896.

Application filed July 25, 1895. Serial No. 557,101. (No model.)

To all whom it may concern:

Be it known that I, JAMES S. HILYARD, a citizen of the United States, residing at Columbus, in the county of Franklin and State 5 of Ohio, have invented certain new and useful Improvements in Washing-Machines; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 This invention relates to certain new and useful improvements in washing-machines; and it has for its object the production of a machine of this character which shall be simple in construction and efficient in operation 20 and which will not readily get out of order or become deranged.

25 The invention comprises the novel features of construction and also the detail combination and arrangement of parts, substantially as hereinafter fully set forth, and particularly pointed out in the claim.

In the accompanying drawings, Figure 1 is a plan view. Fig. 2 is a longitudinal sectional view. Fig. 3 is a cross-sectional view.

30 Referring to the drawings, A designates the tub or water-chamber, which is supported by suitable legs *a* and provided with an outlet-opening *a'* in one end thereof, said opening being normally closed by a plug *a''*.

35 B designates the main rubber, which consists of a frame *b*, having rubber bars *b'* rigidly mounted therein. From the under side of frame *b* depend brackets or bearings *b''*, in which are mounted rollers or casters *b'''*, said 40 rollers being designed to rest on the bottom *a''* of tub A and support the rubber in its operation. To each side of frame *b* and projecting upwardly therefrom are secured arms *b''''*, to the upper end of which are pivotally 45 connected pitmen *b'''''*, said pitmen being also pivotally connected at their other ends to cranked portions *b''''''* of an operating-shaft C. The shaft C is mounted in suitable bearings *b'''''''* on the upper edges of tub A, and the same

may be operated in any preferred manner, as, 50 for instance, by a crank-handle *b''''''''*.

D D are guides for a supplemental rubber E. These guides are removably mounted in grooved brackets *d*, secured to each of the end walls *d'* of chamber A. Each of said 55 guides or supports is cut away at *d''*, so as not to interfere with the cranked portions *b''''''* of shaft C during the revolution of the latter. Flanges *d''* are formed on the lower edges of the guides D, and on these flanges the rubber 60 E is designed to move back and forth in opposite directions to the reciprocal movement of the rubber B, the guides D being mounted directly above said rubber B and serving also to prevent lateral movement of said rubber 65 E. The rubber E is similar in construction to rubber B, the rollers or casters, however, being omitted, and is provided with a central longitudinal bar *e*, to which is secured an upwardly-projecting arm *e'*. To the arm 70 *e'* is pivotally connected one end of an arm or pitman *e''*, which latter is secured at its other end to a cranked portion *e''''* of shaft C.

In operation the supplemental rubber E is first removed or lifted out of tub A, and the 75 latter is then filled to a suitable depth with water. The articles to be washed are then placed on top of rubber B, and the rubber E is then replaced in its position on the flanges *d''*. By the revolution of shaft C the two rubbers are given an alternate back-and-forth 80 movement in opposite directions, thus subjecting the articles to be washed to a very thorough rubbing operation.

The advantages of my improved washing- 85 machine are apparent to those skilled in the art to which it appertains, and it will be specially observed that the same is simple in construction, efficient in operation, cheap and durable.

90 I claim as my invention—

The herein-described washing-machine, comprising a tub or water-chamber, a main rubber mounted on rollers and resting on the bottom of said tub or chamber, grooved 95 brackets secured to the end walls of said tub or water-chamber, longitudinal guides removably mounted in said brackets and hav-

ing flanges projecting from their lower longitudinal edges, an independent supplemental rubber adapted to rest on said flanges, arms projecting upwardly from said main rubber between said guides and the walls of said tub, an arm projecting upwardly from said supplemental rubber, a crank-shaft, and connections between said arms and said crank-shaft, whereby an opposite reciprocal movement is

given to said rubbers, said guides also serving to prevent lateral motion of said supplemental rubber substantially as set forth.

In testimony whereof I affix my signature in presence of two witnesses.

JAMES S. HILYARD.
